UNITED STATES PATENT OFFICE.

JOHN B. GORDON, OF CUTLER, ILLINOIS.

ATTACHMENT FOR ANTI-FREEZING RECEPTACLES.

SPECIFICATION forming part of Letters Patent No. 245,624, dated August 16, 1881.

Application filed January 24, 1881. (No model.)

To all whom it may concern:

Be it known that I, JOHN B. GORDON, a citizen of the United States, residing at Cutler, in the county of Perry and State of Illinois, 5 have invented certain new and useful Improvements in Lamp-Burner Attachments for Anti-Freezers; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification, and in which—

15 Figure 1 shows anti-freezing receptacle or chamber with my improved device arranged in connection therewith. Fig. 2 shows a plan view of my device detached from the aforesaid receptacle, and Fig. 3 is a side view of the 20 same.

This invention relates to lamp-burner attachments adapted particularly for use in connection with receptacles in which canned fruit or vegetables, &c., are stored or kept to avoid 25 freezing; and it consists in combining with such a receptacle having an opening in its bottom, and affixed to said bottom, around said opening, a perforated receiver, a lamp, with its burner provided with a plate adapted to snugly 30 fill the aforesaid opening, and having securing sliding rods entering eyes or staples in the bottom of the receptacle, substantially as hereinafter more fully set forth and claimed.

Referring to the accompanying drawings, A 35 marks an anti-freezing receptacle or chamber, which is referred to for convenience in illustrating the application of my invention. Affixed to the bottom of the aforesaid receptacle, around an opening therein, is a receiver, B, to 40 inclose the lamp, and having perforations or holes to admit air to promote combustion or feed the flame. A door is provided to the receiver B, to open and close it, as occasion may require.

45 C is the lamp, which is supplied with the burner C'. This burner is provided with a plate or flange, a, adapted to fill the opening in the bottom of the receptacle A, and thus cut off an unnecessary inflow of air or cold, 50 while the receiver cuts off extreme cold from

the lamp to protect its contents. The plate or flange a, among other ways, may be connected to the burner by arms reaching out from the latter and fitting in eyes or staples depending from the under side of the flange, as shown in 55 Figs. 1 and 2. Rods b b, sliding in eyes or staples upon the upper side of the flange or plate a, and adapted to fit into eyes or staples e in the bottom of the receptacle A, permit of suspending the lamp in position and its ready 60 attachment to and detachment from the receptacle. The manipulation of the rods is effected through the door of the receptacle.

This device permits of the adjustment of an ordinary lamp to an anti-freezer, for warming 65 the same, in lieu of using a furnace or similar heater.

Instead of making the receiver for the inclosing of the lamp, as shown, it may be formed by extending the sides of the receptacle or 70 anti-freezing chamber below the bottom a suitable distance and attaching thereto a second bottom provided with perforations for the admission of air.

I am aware that it is old to provide the 75 burners of a lamp with a plate filling an opening in the bottom of the receptacle, and to provide the said plate around the burners with upward-extended heat-conducting tubes with a plate attached to their upper ends sliding 80 under a diaphragm and upon flanges or ways.

Having thus fully described my invention, I claim and desire to secure by Letters Patent—

The combination, with an anti-freezing receptacle, A, having an opening in its bottom, and affixed to said bottom, around its opening, a perforated receiver, B, of the lamp C, with its burner C', provided with a plate, a, adapted to snugly fill the opening in the receptacle- 85 bottom, and having the securing sliding rods b entering eyes or staples e in the bottom of the receptacle, substantially as shown and described, for the purpose set forth.

In testimony whereof I affix my signature in 95 presence of two witnesses.

JOHN BRECKENRIDGE GORDON.
